UNITED STATES PATENT OFFICE.

LEWIS BURG, OF DALLAS CITY, ILLINOIS.

AXLE AND AXLE-BOX.

SPECIFICATION forming part of Letters Patent No. 549,103, dated November 5, 1895.

Application filed August 9, 1895. Serial No. 558,740. (No model.)

To all whom it may concern:

Be it known that I, LEWIS BURG, a citizen of the United States, residing at Dallas City, in the county of Hancock and State of Illinois, have invented certain new and useful Improvements in Axles and Axle-Boxes; and I do hereby declare the following to be a full, clear, and exact description of the invention, such as will enable others skilled in the art 5 to which it appertains to make and use the same, reference being had to the accompanying drawings, which form part of this specification.

My invention relates to axles and axle-boxes, and has for its object to provide superior means for lubricating the axle and to more effectually exclude foreign matter from the bearing parts; and with this end in view my invention consists in the several improvements 15 of construction and arrangement of parts hereinafter fully described, and more particularly pointed out in the claims.

Referring to the drawings, Figure 1 is a longitudinal sectional view of an axle and axle-box embodying my improvements. Fig. 2 is a cross-sectional view taken on the line xx of Fig. 1. Fig. 3 is a perspective view of a portion of the axle-arm, showing the position of the grooves for oil and the communication between them; and Fig. 4 is a sectional perspective view of a portion of the axle-box.

Similar letters of reference indicate corresponding parts in each figure of the drawings. 35 A represents the axle-arm, and B a cap extending from the axle-bed over the inner end of the arm, an annular space being thus formed between the axle-arm and the cap. The cap B is preferably an integral part of 40 the axle, as shown in the drawings; but it may be of a separate piece of metal rigidly secured to the axle by any suitable means. The bearing part a of the axle-arm is tapered in the usual manner and is provided with 45 two longitudinal grooves c and d , the former being on top and the latter on the side of the axle. These two grooves are connected by three or more passages e , extending through the axle-arm diagonally to its vertical center, as shown in Figs. 2 and 3, the functions 50 of which will hereinafter be explained.

F represents the axle-box, adapted to be

fitted in the hub of the wheel in the usual manner. This box has a tapered bearing portion f , which fits on the tapered portion a 55 of the axle-arm and revolves thereon. The tapered portion of the box has two oppositely-arranged longitudinal grooves g in its inner surface, as indicated in the drawings. These grooves are preferably of the same length as 60 the grooves c and d in the axle-arm. The inner end h of the axle-box is enlarged to such an extent as to leave a space between it and the inner enlarged part C of the axle-arm, which is inclosed thereby. The end of 65 the box h is provided with two exterior collars i , which fit loosely within the cap B, and a washer j , of rubber or other suitable material, is placed between the collars i and fits snugly against the inner surface of the cap. 70 The inner end of the box F abuts against a leather washer k , which surrounds the extreme inner end of the axle-arm and abuts against the end wall of the cap B.

The enlarged portion C of the axle-arm has 75 two circumferential grooves l , in which are washers m , of rubber or other suitable material, said washers being of sufficient diameter to frictionally engage the inner surface of the enlarged portion h of the axle-box. A 80 leather washer n , which fits over the bearing-arm a , is interposed between the outer end of the enlarged part of the axle-arm and the outer end of the interior of the part h of the axle-box.

That portion of the axle-arm between the grooves l is circumferentially grooved, as indicated at G. The object of this groove is to collect and hold any foreign matter which may chance to work past the washers j , k , 90 l and m into the axle-box.

The outer end of the axle-arm is screw-threaded for the reception of the nut H, which is screwed up against the end of the axle-box, a leather washer q being used in the nut in 95 the ordinary manner. Over the nut H a cap-nut I is screwed on the end of the axle-box and revolves with it and effectually prevents any dust or other foreign matter from reaching the bearing-surface from the outer end of the 100 axle-arm.

From the foregoing description it will be seen that all foreign matter will be effectually excluded from the bearing portion of the axle,

which is the tapered portion only, for even should any foreign matter find its way to the axle-arm past the washers *j* and *k* and the rear washer *m* it will be effectually prevented 5 from passing farther by the groove *G* and the front washer *n*. The fact, also, that there is no bearing on the axle-arm in the rear of the washer *n* still further aids to exclude 10 foreign matter from the tapered bearing-surface, since it cannot be worked along to that part, as might be the case if the rear end of the axle-arm was in frictional contact with the axle-box.

In order to keep the bearing-surface perfectly lubricated, one of the grooves *g* in the axle-box should be filled with oil; also the top groove *c* in the axle-arm. The oil will pass from the upper groove in the axle-arm to groove *d* through the passages *e* and lubricate the bearing-surface as the wheel revolves, while the surplus oil will be carried in the groove *g* and emptied therefrom into the grooves *c* at the top of the axle. By this 25 means of circulation when the wheel is revolved the oil will be kept constantly moving and a perfect lubrication of the whole bearing-surface will be effected.

Having thus fully described my invention, what I claim as new, and desire to secure by 30 Letters Patent, is—

1. The combination with an axle arm having a tapered bearing portion and an enlarged rear portion connecting the bearing portion to the axle bed, of a cap projecting from the 35 axle bed over the rear portion of the axle arm to form an annular space between them, an axle box having a tapered portion over the bearing surface of the axle and an enlarged rear portion to surround the rear of

the axle arm and not in contact therewith, 40 exterior collars on the rear end of the axle box fitting loosely within said cap, and a series of washers interposed between the axle arm, the axle box and the cap, substantially as set forth.

2. The combination with an axle arm having a tapered bearing surface and an enlarged rear portion connecting the tapered portion with the axle bed and having three circumferential grooves, of a cap projecting from 50 the axle bed over the rear portion of the axle arm to form an annular space between them, an axle box having a tapered portion to fit on the bearing surface of the axle arm, and an enlarged rear portion to surround the rear 55 of the axle arm and not in contact therewith, exterior collars on the rear of the axle box fitting loosely within said cap, a washer between said collars, washers in the two end grooves of the axle arm, a nut on the outer 60 end of the axle arm, and a cap secured on the outer end of the axle box to inclose the nut, substantially as set forth.

3. The combination with an axle box having oppositely arranged grooves on its inner 65 surface, of an axle arm fitting within the said box and having a longitudinal groove on its upper surface and another groove on its side and passages formed through the axle diagonally to its vertical center to connect 70 said grooves, substantially as and for the purpose set forth.

In testimony whereof I affix my signature in presence of two witnesses.

LEWIS BURG.
